RECORD CHANGER

Rudolph A. Bucwar, Chicago, Ill., assignor to
Galvin Manufacturing Corporation, Chicago,
Ill., a corporation of Illinois

Original application May 10, 1940, Serial No.
334,414. Divided and this application August
24, 1942, Serial No. 456,109

6 Claims. (Cl. 274—10)

This invention relates generally to record changing means for a sound reproducing machine, and in particular to a record changer adapted to automatically change a plurality of records in succession, the invention being particularly applicable for the changing of the records of disc type having off center or eccentric grooves, which are continuous with and formed at the end of the musical grooves. This application is a division of application Serial No. 334,414 filed May 10, 1940 which issued August 25, 1942 as Patent No. 2,293,703.

An object of this invention is to provide an improved phonograph of the type adapted to play a stack of records in succession.

Yet another object of this invention is to provide a record changer for successively releasing into a playing position the lowermost record of a stack of records regardless of the relative thickness of the records in the stack.

A further object of this invention is to provide a phonograph having means for successively releasing the lowermost record of a stack of records into a playing position, and including a vertically extended center support with record retaining means spaced upwardly therefrom, and an edge support adapted to tilt the record stack relative to the center support so that the lowermost record is always free of the retaining means regardless of any variations in the thickness of the records.

A still further object of this invention is to provide a record changer adapted for use with either ten inch or twelve inch records, in which a support for supporting the edge of a plurality of records stacked above a turntable is adapted to position stack, in correspondence with the diameter of the records therein, relative to the means for releasing successive records into a playing position on the turntable, to provide for a positive operation of the releasing means for records of widely varying thicknesses.

Another object of this invention is to provide an automatic record changer which is simple, compact and rugged in construction, positive and efficient in operation and comprised of a minimum of parts requiring adjustment.

A feature of this invention is found in the provision of a phonograph for successively playing a stack of either ten inch or twelve inch records, in which the records are supported above a playing position by a vertically extending center support and an edge support, the records being retained in a supported position by means spaced upwardly from the center support. The edge support is selectively movable to tilt or incline a stack of ten inch records in a reversed direction relative to a stack of twelve inch records to vary the effective clearance between the lowermost record in the stack and the record

retaining means so regardless of any variations in the thickness of the records, in the particular stack being played, the lowermost record is always free of the retaining means for release from the center and edge supports into a playing position.

Yet another feature of this invention is found in the provision of a phonograph in which a stack of records are supported above a turntable by a vertically extending spindle having a center support thereon for the records, and an edge support. The records are retained on the two supports by means vertically spaced above the center support and positioned through the records. An ejector portion at the center support is operable to move the lowermost record of the stack from the two supports for dropping about the spindle into a playing position on the turntable. The edge support is located out of a horizontal plane through the center support and normal to the axis of the spindle to vary the effective clearance between the retaining means and the lowermost record so that such record regardless of its thickness, is always free of the aligning means for release into a playing position.

Further objects, features, and advantages of this invention will become apparent from the following description when taken in connection with the accompanying drawings in which:

Fig. 1 is a plan view of the invention showing the arrangement of the driving system for the automatic record changer;

Fig. 2 is a view in perspective of the operating cam for the record changing mechanism;

Fig. 3 is an electrical diagram showing the control circuit for the record-changing mechanism;

Fig. 4 is a view partly in section as seen on line 4—4 in Fig. 5;

Fig. 5 is a sectional view taken approximately along the line 5—5 in Fig. 4;

Fig. 6 is a fragmentary sectional view taken on line 6—6 in Fig. 4;

Fig. 7 is a fragmentary sectional view taken on line 7—7 in Fig. 4;

Fig. 8 is a view illustrated similarly to Fig. 7 showing the parts thereof in a changed position;

Fig. 9 is a developed view of the cam portion enclosed between the lines 9—9 in Fig. 4; and

Fig. 10 is an enlarged fragmentary longitudinal sectional view of the turntable spindle showing the assembly of the record releasing means thereon.

In the practice of this invention the unplayed records are supported in a stacked relation above the turntable of the phonograph or like machine and successively released for dropping into a playing position on the turntable. The record supporting means includes a vertically extending center support and a portion for retaining the records aligned on the center support. A mov-

able edge support for the records is illustrated in the drawings as having a pair of shelves or platform portions of different lengths each of which is selectively movable to a position to support a stack of records of a certain size, as for example a stack of ten inch or twelve inch records. It is well known of course that records of the same size may vary in thickness. To provide for a successive releasing of the records into a playing position regardless of the particular size of the stack of records being played or the relative thicknesses thereof, the shelf portions of the edge support are vertically spaced from each other to support the ten inch and twelve inch records so that they are reversely tilted relative to the center support. This reversed tilting of a stack of ten inch and twelve inch records serves to position the lowermost record of a corresponding stack of records free of the aligning portion at the record center support, while retaining the remaining records in the record stack in an engaging position with the aligning portion. As a result regardless of whether ten inch or twelve inch records are being played, or the relative thicknesses of the records in a stack, such records are adapted to be successively released into a playing position on the turntable by merely operating the edge support to move into a record supporting position the shelf portion corresponding to the particular size of the records being played. The record-releasing means is operated by a cam mechanism, including a multiple operating cam which is located below the turntable and adapted to provide for a raising of the tone arm from the record in playing position and for a moving of the arm beyond the circumference of such record prior to the actuation of the record releasing means.

There is illustrated in Figs. 1 and 5 the usual frame structure 20, turntable 21, and tone arm 22 for a phonograph or like machine, the turntable 21 being shown with a record 72 supported thereon. The turntable is driven by a low voltage induction motor 23 carried in a suitable manner on the structure 20, the motor shaft being provided with a pulley 24 which is in frictional engagement with the turntable driving pulley 26 which in turn is in frictional engagement with the table rim 21. A shaft or spindle 28 secured to the frame or wall 20 in an obvious manner by the clamping action of the shoulder 29 and nut 31, rotatably supports the turntable, the hub portion of which includes a pulley 32 which is in driving connection with an idler pulley 33 through a flexible spring drive 34. The pulley 33 is mounted at the upper end of a countershaft 36 which is rotatably supported in a bushing member 37, the member 37 being suitably secured in the wall 20 as by welding or like means. An idler pulley 38 is fastened to the lower end of the countershaft 36 by screw means such as 39, the pulley 38 being in driving connection with a pulley 41 which is rotatably mounted at the lower end of a stub shaft 42; the shaft 42 being mounted in the wall 20 by screw means 43 and the pulley 41 being maintained on the shaft 42 by screw means 44. Pulleys 33 and 38 act as reduction pulleys between the pulleys 32 and 41, with the entire pulley system being in operation concurrently with an operation of the motor 23. A serrated flange 46 formed on the upper side of the pulley 41 provides for a driving engagement of the pulley 41 with an operating cam 47 in a manner to be later fully described.

The cam 47 (Figs. 2, 4 and 5) is of substan-

tially dish form, having a bottom 48 and an outer wall 49, and may be suitably formed as by die casting or like means. The wall 49 is provided with an outwardly projecting annular flange or peripheral rim 51, which has cam faces or working surfaces 52 and 53 formed on opposite sides thereof, the low portion or spot 54 of the upper cam 52 being substantially opposite the high spot 56 of the lower cam 53 (Figs. 2 and 9). Cam followers 57 and 58, in operative association with the cam surfaces 52 and 53, respectively, are angularly spaced relative to each other so that the operative effects provided by the low and high spots, 54 and 56, respectively, in the operation of the record-changing mechanism occur in sequence rather than concurrently as will be later fully described. An inner wall 59 projects upwardly from the cam bottom 48 and includes a portion of the cam hub 61, the wall 59 being continuous in extent and substantially equal in height to the outer wall 49, with the vertical surface 62 thereof acting as a cam face or working surface for a corresponding cam follower 63. The portion of the cam surface 62, which is included between the lines 64, is of corresponding contour with the oppositely disposed inner side of the wall 49 to form a guiding slot 65 for the follower 63. It is thus seen that a closed recess 66 is formed within the inner wall 59 and a groove 67 of varying width between the walls 49 and 59. The groove 67 is of uniform width and guiding to the follower 63 only between the lines 64 at the slot 65 and is of varying width over its remaining length, its greatest width being in the zone designated as 68 which occurs at the end of the slot 65 and between the hub 61 and a confining wall 60 adjacent the low spot 54 of cam surface 52, for a purpose to be later fully explained. The outer wall 49 near the end of the slot 65 is increased in section to accommodate an aperture or opening 69 of a size to receive therein a pivotal lever or pawl 71 which is adapted for engagement with the serrated flange 46 of the pulley 41, in a manner to be hereinafter described.

Actuation of the cam follower 57 on movement of the cam 52 is adapted to provide for a lifting or a lowering of the tone arm 22 from the turntable 21, and specifically from a record 72 which is supported in a playing position on the turntable (Fig. 5). The follower 57 is of angular shape and includes a straight portion 73 and a bent portion 74, the portion 74 being inclined upwardly into the hollow tone arm 22. The straight portion 73 is slidably and rotatably supported in a sleeve member 76, which in turn is rotatably supported in a bearing block or bushing 77, which is suitably mounted on the frame 20. The bent portion 74 is adapted to engage the upper side of the tone arm 22 which is pivoted at 78 to a supporting leg member 79 which in turn is rotatably supported on the bushing 77. The upper end of the sleeve 76 is secured to the member 79, by welding or like means, so that the sleeve 76 is angularly or rotatably movable with the tone arm 22 through the leg member 79. It is thus seen that the operating position of the cam follower 57 relative to the tone arm 22 remains unchanged during any swinging movement of the arm across the record 72.

The lower end of the sleeve 76 projects outwardly from the bushing 77 to provide for a mounting at such end of a rocker arm 81, the arm and sleeve being held together in frictional engagement by means of a holding screw 82 or

like means. The free end of the arm 81 (Fig. 4) is pivotally connected at 83 to the end portion 84 of a selector link or lever arm 86, the end portion 84 being of sufficient width to also provide for the rotatable mounting therein of the cam follower 63 at a distance from the pivotal connection 83. Angular movement of the rocker arm 81 and hence of the sleeve 76 and tone arm 22 in one direction is thus obtained on actuation of the cam follower 63 by the cam 62. The end 87 of the lever arm 86 is provided with a slot 88 to slidably receive therein a pin member 89 which is mounted in a flat plate or selector disc 91.

The disc 91 is mounted at the lower end of a shaft 92 (Fig. 6) as by welding or like means, the shaft 92 being rotatably supported in a bushing or sleeve 93, which is suitably secured to the cabinet wall 20. The upper end of the shaft is pinned-connected, as indicated as P in Fig. 5, to a platform or shelf 94 of curved contour which is adapted to provide an edge support for a stack of records 95 located vertically above the turntable 21, the shelf 94 being rotatably supported on the upper end of the sleeve or stand 93. As shown in Fig. 1, the projected surface area of the shelf is of substantially rectangular form, the shelf being positioned on the stand 93 in a manner to provide for unequal shelf lengths 96 and 97 on opposite sides of the stand. A rotation of the shelf of 180 degrees thus provides for a supporting shelf of a different length for records of different diameter, the short length 96 being adapted to support the stack of twelve inch records 95 and the long length 97 being adapted to support a stack of ten inch records 100, in a manner to be hereinafter fully described.

The 180 degree rotation of the shaft 92 moves the end 87 of the selector arm 86 from one side of the shaft 92 to the other side thereof through the sliding action of the pin 89 in the slot 88 (Fig. 4), the limits of rotation being defined by the engagement of the notches 98 in the selector disc 91 with the pin 99 in the spring-tensioned pivotal indexing lever 101. When the record edge support 94 is positioned to support ten inch records the arm 86 is in the position indicated by the dot-dash lines. On rotating the support 94 to accommodate twelve inch records the arm 86 is moved to the position indicated by the full lines, this movement of the arm 86 providing for a movement of the rocker arm 81 and specifically the pivotal connection 83 thereof relative to the cam follower 63, the position of which is practically unchanged on movement of arm 86 by rotation of the support. Since the angular movement of the rocker arm 81 controls directly the angular movement or swing of the tone arm 22, the movement of the rocker arm downwardly to the left as seen in Fig. 4 provides for an initial starting position of the tone arm 22 on the record 72 to be played, at an increased distance from the circumference of the turntable 21, the dotted lines representing the starting position of the tone arm 22 when the platform 94 is positioned to accommodate twelve inch records and the dot-dash lines indicating the starting position of the tone arm 22 when ten inch records are to be played. It is thus seen that after a positioning of the platform 94 in correspondence with the diameter of the records to be played, the operation of the roller 63 by the cam 62 and the roller 54 by the cam 52 controls the swing of the tone arm 22 and the lift of the arm 22, respectively, relative to the record being played.

The cam follower 58, which is operatively as-

sociated with the cam face 52 of the multiple cam 47, is rotatably mounted at one end of a crank arm 102 which is pivotally supported in a bearing member 103 suspended from the cabinet wall 20 (Figs. 4 and 5). The opposite end 104 of the crank arm 102 is provided with an adjusting screw 106 which is adapted to abuttingly engage the lower end of an operating member 107 which is slidably supported axially of the spindle or shaft 28 (Fig. 5). The spindle 28 is formed with an off-set upper portion 108 to form a shoulder 109, the shoulder 109 acting as a center support for the stack of unplayed records which are located above the turntable 21.

15 An eccentric cap or sleeve member 111 substantially equal in diameter to the body portion of the spindle 28 is rotatably mounted about the offset portion. In the positioning of a stack of records above the turntable 21 the sleeve 111 is rotated until substantially its thinnest wall section 112 is positioned at the shoulder 109 to provide for an alignment of the records on the shoulder (Fig. 10).

25 A trigger or trip lever 113 is pivotally connected at 114 to the shaft 28 and is completely retractable in an axially extending groove 116 formed therein, an opening 117 being provided in the bottom of the groove above the shoulder 109. An inclined side portion 118 at the lower 30 end of the lever is adapted for slidable engagement with the upper end of the operating member 107, to provide for an outward movement of a nose or projecting finger 119, formed at the upper end of the lever 113, through the opening 117 immediately above the shoulder 109 for a purpose to be later described. On retraction of the member 107 from its engagement with the side portion 118, as by the spring-retained means 121 (Fig. 5), the finger 119 is removed from the 35 opening 117 by a spring 122 arranged in compression in the spindle 28 between the lever 113 and the bottom of the groove 116. The pivotal movement of the trip lever 113 by the operating member 107 provides for an engagement of the finger 119 with the lowermost or bottom record 95' at the aperture 123 formed at the center of the record. Since the finger 119 is of a length to extend completely over the shoulder 109, the record 95' is pushed clear of the shoulder and into 40 centering engagement about the lower portion of the spindle 28, the spindle being of a diameter somewhat less than the diameter of the record aperture 123. Since the lever 113 is completely retractable within the spindle 28 the record 95' is thus entirely released and free to fall into a playing position on the turntable 21.

45 As is best illustrated in Fig. 5, the shoulder or center support 109 is of a depth commensurate with the extent or length of the support given the edges of the records 95 by the supporting platform 94. The movement of the lowermost record 95' from the shoulder 109 is thus sufficient to effect a complete separation of the record 95' from the platform 94, so that the record is entirely unsupported in its drop to the turntable 21, except for its centering engagement about the spindle 28. The trigger or record releasing means 113 is thus operable to provide for a separation or release of a record 95', from a stack of unplayed records 95, by engaging the record at its immediate central portion at the aperture 123.

50 In the arrangement of the records 100 and 95 in a stacked formation it is readily apparent that considerable friction may occur between the low-

ermost record 100' and 95' and the next adjacent record 100A and 95A, respectively. Since this frictional factor similarly effects the ten inch and twelve inch records the following description will refer to the twelve inch records. Particularly when the stack 95 is rather high this friction will tend to provide for a movement of the record 95A with the record 95' during the record-releasing operation. Also, it is well-known that records of the same diameter differ widely in thickness and that twelve inch records are generally of a greater thickness than ten inch records. The supporting shelf 94, therefore, is adapted to position the records 95 on the shoulder 109 to provide for a positive engagement of the finger 119 with the lowermost record 95', and of the eccentric sleeve member 112 with the record 95A, irrespective of the relative thicknesses of such records, to prevent any moving of the record 95A with the record 95' when it is being pushed from the shoulder 109.

With reference to Figs. 5 and 10 the lower end of the eccentric cap member 112 is illustrated as being located above the shoulder 109 a distance indicated by the lines A—B, the finger 119 being adapted for projection through the opening 117 formed between the shoulder and such lower end. In the horizontal positioning of the records 95, that is at right angles to the spindle 28, it is readily understood that the distance between the shoulder 109 and the lower end of the cap member 112, should correspond to the thickness of an unusually thick twelve inch record to assure the release of all twelve inch records on actuation of the lever 113. However, in some cases, it might happen that this provision for a very thick twelve inch record would result in the space between the shoulder 109 and cap member 112 being sufficiently great to exceed in extent the combined thicknesses of two ten inch records, which are thinner than the usual ten inch records. In the event two such records were positioned adjacent each other it is apparent that both records might be released at one time by the releasing lever 113. To provide for a positive operation of the releasing means to release only one record, irrespective of the relative thicknesses of the records in the stacks 95 and 100, the ends 96 and 97 of the supporting shelf 94 are vertically offset from each other, so that the end portion 96 which is adapted for the support of the twelve inch records is below horizontal alignment with the shoulder 109 and the ten inch record supporting portion is above horizontal alignment with the shoulder 109. The twelve inch records, which are illustrated in Fig. 10 in full lines, are thus tilted or inclined in one direction relative to the shoulder 109 so that the portion 90 of the powermost record 95' is dropped below the wall portion 126 of the cap member 112 to a point lower than it would occupy if the record was in a horizontal position. The record 95' is thus entirely clear of the wall portion 126 to provide for its dropping into a playing position on the turntable 21 on operation of the trip lever 113. In the playing of ten inch records, which are illustrated in Figs. 5 and 10 in dotted lines, the shelf portion 97 provides for a tilting of the record 100' in a direction from the shoulder 109 reversed relative to the angle of support for the twelve inch records so as to raise the record portion 90' of record 100A into positive arrangement with the wall portion 126. The record 100', therefore, is alone moved from the shoulder 109 on actuation of the trip lever 113. By virtue of the reversed tilting of the records

95' and 100' relative to a horizontal plane through the shoulder 109 the distance A—B is less than the distance which would normally be required between the shoulder 109 and cap member 112 to accommodate an extra thick twelve inch record when horizontally positioned while providing for a positive successive releasing of all ten and twelve inch records, irrespective of the thickness of such records. It is to be understood that the nose or projecting finger 119 is of a size commensurate with the thickness of the thinnest record which might be played, so that engagement of the nose with only one record will be made regardless of the thickness of such record. When all of the records such as 95 or 100 have been played and it is desired to remove the records from the turntable 21, the member 111 is rotated to the position illustrated in dotted lines in Fig. 5, to form a shaft or spindle 28 which is in peripheral alignment over its entire length. Since the pivotal lever 113 is completely retractable within the spindle 128, the spindle is thus unobstructed over its entire length, so that the records successively positioned on the turntable 21 may all be removed at one time and in a stack from the spindle 28. It is understood, of course, that prior to the lifting of the records from the spindle the shelf 94 is rotated out of its engaging position with the records 95 or 100 and into a position with a longitudinal side facing the spindle 28, so as to be clear of the records being lifted from the turntable 21.

The operation of the above described record-changing apparatus is controlled through an electric control circuit which is closed in response to a predetermined operating position of the tone arm 22 on the record 12, supported in playing position on the turntable 21. The circuit (Fig. 3) is illustrated as adapted for energization from a suitable electrical source through a transformer 127 and includes a solenoid 128, a lock out switch 129, a control switch 131 and a reject button 132; the switch 131 and reject button 132 being arranged in parallel to provide for separate closing of the circuit.

The solenoid 128 (Fig. 4) is supported in a frame member 133 depending from the wall 20, the solenoid being arranged in a position above the pulley 41 and near the circumference of the cam 47. An armature 134 electrically associated with the solenoid is pivotally connected to the frame member 133, the connecting pin 136 in the member 133 being also slidable in the elongated slot 137 formed in the armature, for a purpose to be later described. The armature 134 is of substantially angular cross-section, one leg 138 thereof being magnetically attractive to the solenoid 128 and the other leg 139 acting as a supporting shelf for the dog or pawl member 71 which is pivotally connected to the cam 47 and arranged within the opening 69. The dog 71 is adapted for engagement with one of the serrations in the serrated flange 46 to provide for a driving of the cam 47 by the continuously rotating pulley 41; the spring 141 serving to bias the dog into an engaging position with a serration (Fig. 7). When the solenoid 128 is not energized the armature 134 is urged into a supporting or holding position with the dog 71 by a spring 142, which is connected at one end to the member 133 and at its opposite end to the armature 134 (Fig. 8). The armature 134 and dog 71 thus act as a clutch, which is operable to provide for a driving of the cam 47 by the pulley 41, which in turn is driven by the turntable motor 23. Con-

trol switch 131 is comprised of a pair of contact arms 143 which are mounted on a frame 144 depending from the wall 20, the arms being suitably insulated from the frame 144 and from each other by insulating member 146. The gap between the arms 143 is adjusted by an adjustable cam 147 which is held in the frame plate 20, the cam being in sliding engagement with the outer one of the contact arms 143. Adjustment is thus readily made by turning the cam 147, which moves the outer contact arm 143 relative to the inner contact arm, to provide for a variation in the gap between the arms. The free end of the outer contact arm is provided with a flat extension or plate 148 which is adapted for frictional engagement with a pair of spaced fingers 149 (Figs. 4 and 6), the fingers 149 being mounted on the rocker arm 81 and hence movable with the rocker arm so as to move with the tone arm 22 in its travel across the record 72 being played.

The operation of the invention is best understood from Fig. 4 in which the multiple or operating cam 47 and its associated cam followers are illustrated in the positions which they assume when the tone arm 22 is in a starting position on the record to be played, the record 72 being indicated from the full line position of the rocker arm 81, as a twelve inch record although it is to be understood that the operation is the same for either a ten or a twelve inch record. This operating condition represents a neutral position of the cam 47, the cam being out of engagement with the pulley 41 and the spaced fingers 149 being out of engagement with the projecting plate 148 of the outer contact arm 143. As the tone arm 22 moves inwardly across the record 72 toward the spindle 28 the rocker arm 81 is moved inwardly toward the shaft 42, the follower 63 being out of contact with the cam surface 62 and moving freely in the widened portion 68 of the groove 67 during the entire playing of the record, with the follower 57 being at the low spot 54 of the cam 52 and the follower 58 being in engagement with the low portion of the cam 53 (Figs. 2 and 9); the confining wall 60 serving to maintain the follower 63 within the zone 68 and out of any possible engagement or interference with the follower 57. When the tone arm 22 is in partial traversal of the record 72 the fingers 149 frictionally engage the plate 148, but since the pressure exerted by the fingers on the plate is in a direction to maintain open the contact arms 143, that is in a direction urging the outer contact arm against the cam 147, the control or solenoid circuit is maintained open. However, on the record being completed the tone arm is carried to the eccentric groove 151 (Fig. 1) which is formed at the center of the record, to provide for an oscillating movement of the tone arm on the record. When the tone arm is first moved outward in a direction away from the spindle 28, by its oscillating movement in the groove 151, the fingers on rocker arm 81 are moved in a direction towards the shaft 42, which movement provides for a pulling inwardly of the outer contact arm 143 away from the cam 147 and into contact with the inner contact arm whereby to close the control circuit for the record changing apparatus, the circuit being comprised of conductor 152, solenoid 128, the closed switch 129, control switch 131 and conductor 153.

Closing of the control circuit by the contact arms 143 energizes the solenoid 128 to provide for an actuation of the armature 134 to release the dog 71 for engagement with the pulley 41,

rotation of the cam 47 being obtained immediately upon the engagement of the dog 71 because of the continuous rotation of the pulley 41. In the rotation of the cam 47 in a clockwise direction, as seen in Fig. 4, the cam face 52 acts first to operate the cam follower 57 to raise the tone arm 22 from the record 72 prior to any outward swinging or angular movement of the arm towards the circumference of the record. After the arm 22 has been raised to clear the record, the cam follower 63 is engaged by the cam 62 to effect a movement of the tone arm 22 outward from the spindle 28 towards the circumference of the record, the cam follower 57 continuing to ride on the high portion of the cam 52 to hold the arm 22 in a lifted position and the follower 58 being in engagement with the low portion of the cam 53. When the tone arm 22 has been moved to its outermost position and completely off the face of the record 72, which position is indicated on the cam 62 by the portion between the lines 154, the cam follower 58 is engaged by the high spot 56 of the cam 53 to provide for an actuation of the operating member 107 (Fig. 5) by the crank arm 102, the operating member 107 moving the pivotal lever 113 to release the bottom record 95' of the stack of records 95 from its supported position on the center support 109 and edge support 96, in the manner previously fully described. The record 95' is thus dropped into a playing position on the turntable 21 only after the tone arm 22 is completely removed from the face of the record 72 which has been played. After release of the record 95' into a playing position on the turntable 22, the cam follower 63 continues its travel in the groove 65 to provide for a movement of the tone arm inwardly toward the circumference of the turntable 21, the cam 52 and cam follower 57 operating concurrently to provide for a lowering of the tone arm in operative engagement on the newly positioned record.

During the rotation of the cam 47 the fingers 149 are disengaged from the outer contact arm 143 on movement of the rocker arm 81 outwardly from the shaft 42 by the operation of the cam 62 and its associated follower 63 whereby the solenoid circuit is opened to provide a release of the armature 134, which is immediately pulled back into an engaging position with the dog 71 by the spring 142. On a continued rotation of the cam 47, the dog 71 is returned to its starting position where it is engaged by the armature 134 and lifted out of its engagement with the serrated flange portion 46 of the pulley 41, to immediately stop any further rotation of the cam 47. The armature 134 does not operate to abruptly disengage the dog 71 from the pulley 41, but serves to gradually lift the dog 71 away from the engaged serration by the sliding action of the armature 134 as permitted by the elongated slot 137 formed therein. This manner disengaging the dog 71 effects a smoothness of operation of the record-changing mechanism by the reduction of any sudden shocks to the rotating system. The record-changing mechanism is thus returned to its original neutral position and conditioned for the playing of a new record during substantially one complete revolution of the cam 47.

The moving of the contact arms 143 into a closed position by the fingers 149, as explained above, provides for an energization of the solenoid 128 and an immediate release of the dog 71 by the armature 134 for engagement with the serrated flange 46 of pulley 41, the fingers being initially moved toward the shaft 42 by the os-

oscillating motion of the tone arm 22 in the eccentric groove 151. Since the oscillating motion of the arm 22 in the groove 151 also effects a movement of the fingers 149 in an outward direction from the shaft 42 alternately with the movement toward the shaft, a condition might occur where the arms 143 are successively opened and closed before the tone arm 22 is lifted completely out of engagement with the record, such as 12, which is being played, whereby to provide for a repeat operation of the solenoid or relay 128. This repeat operation, however, does not effect any further control of the record-changing mechanism, since the dog 71 on initial actuation of the solenoid 128 is immediately engaged by the pulley 41 and rotated out of an engaging position with the armature 134. The repeat operation, therefore, acts only to move the armature 134, which movement is accompanied by the usual "clicking" noise. To prevent a repeat operation of the solenoid 128 and the resulting "clicking" noise, the control circuit (Fig. 3) is provided with a lock out or cam switch 129, which, as illustrated in Figs. 4 and 6, is comprised of spring contact arms 156 and 157 which are suitably supported on the mounting member 144. The contact arm 157 is provided at its free end with an insulating contact or button 158 which is adapted for engagement with the high portion or spot 56 of cam 53. As is best shown in Fig. 9 this engagement maintains the contact arms 156 and 157 in a closed position when the record-changing mechanism is in its neutral position, the arms 156 and 157 being adapted to open on about the first 5 degrees of rotation of the cam 47, which rotation is sufficient to move the cam portion 56 out of engagement with the button 158. Immediately after the start of rotation of the cam 47, therefore, the button 158 is free of the cam and does not contact the low portion 159 of the cam face 53. It is thus seen that on the initial closing of the contact arms 143 and resulting rotation of the multiple cam 47, the control circuit is opened by the opening of the contact arms 156 and 157 so that a second or repeat closing of the arm 143 is rendered ineffective in energizing the solenoid 128 to actuate the armature 134, the contact arms 156 and 157 remaining in an opened position until the operating cam 47 returns to its neutral position.

In the event it is desired to change the record 12, after it has been only partly played, the reject button 132 (Fig. 3) is operable to effect an immediate energization of the solenoid 128 independently of the relative positions of the contact arms 143, the solenoid circuit being complete through conductor 152, solenoid 128, closed cam switch 129, reject button or switch 132 and conductor 153, energization of the solenoid acting to release the armature 134 to effect an engagement of the dog 71 with the pulley 41 in the manner above noted. On rotation of the cam 47 the operation of the record-changing mechanism is similar to that just described.

The invention is thus seen to provide for a record-changing mechanism which is of simple construction, cheap in cost and which is positively controlled during its operation by electrical means in response to a predetermined operating position of the tone arm on the record being played. A start of operation of the mechanism substantially immediately upon the completion of the playing of a record and the provision of means for stopping the record-changing mechanism immediately after its cycle of operation re-

duces to a minimum the time required for the changing of a record. The invention further provides an edge support 94 for a plurality of either ten inch or twelve inch records positioned above the turntable 21, which is adapted to position the records in a manner to provide for a positive release, by the record-releasing means, of only the lowermost record of the stack of records, regardless of the relative thicknesses of the records in such stack. The record-changing mechanism is thus adapted for an efficient operation with either ten inch or twelve inch records and its operation is equally efficient for all records irrespective of their thickness.

It is to be understood that although the invention has been described with particular reference to ten and twelve inch records, it is not to be so limited. It is to be understood also that only a preferred embodiment of the invention has been illustrated and described herein and that modifications and alterations thereof can be made which are within the full intended scope of the invention as defined by the appended claims.

I claim:

1. In a sound reproducing unit for playing a stack of 10 inch or 12 inch records including a rotary turntable for supporting a record in playing position, means for supporting a stack of records above said turntable including a stationary spindle centered relative to said turntable and extending upwardly therefrom, said spindle having an off-set top portion with a shoulder at the bottom of said top portion for supporting the center of said records, means on said top portion for aligning said records for support on said shoulder, with the bottom of said aligning means being spaced from said shoulder a distance less than the thickness of a 12 inch record, movable means for supporting the edge of said records including a plurality of shelf portions of different lengths corresponding to a stack of 10 inch and 12 inch records, said shelf portions being vertically off-set relative to each other and to said shoulder so that a stack of 10 inch records and a stack of 12 inch records are reversely inclined at an angle relative to the horizontal plane of said shoulder, said angle serving to position the bottom record of a stack of either 10 inch or 12 inch records on said shoulder free of said aligning means while retaining the remaining records in engagement with said aligning means, and means in said center support individually engaging the bottom records in succession and moving the engaged record from said shoulder and said edge supporting means so that it drops into a playing position on said turntable.

2. In a sound reproducing unit having a rotary turntable for supporting a record in playing position, means for supporting a stack of records above said turntable including a movable edge support for said stack of records having a plurality of shelf portions of different lengths thereon, with movement of said edge support to a selected position moving a shelf portion to support the edge of a stack of records of a certain size, a stationary spindle centered relative to said turntable and extending upwardly therefrom, said spindle having an off-set top portion with a shoulder at the bottom of said top portion for supporting the center of said records, with said records being positioned about said top portion, means on said top portion for aligning said records for support on said shoulder and edge support, the said shelf por-

tions on said edge support being vertically offset relative to each other and to said shoulder so that said records are inclined relative to the horizontal plane of said shoulder at an angle which is dependent upon the selected position of said movable edge support, said supporting angle serving to position the bottom one of said records on said shoulder free of said aligning means while retaining the remaining records in engagement with said aligning means, and a record ejector in said center support movable over said shoulder for individually releasing in succession the lowermost one of said records from said center and edge support into a playing position on said turntable.

3. In a sound reproducing unit, the combination with a rotary turntable for supporting a record in playing position, of means for supporting a stack of records above said turntable including a stationary spindle centered relative to said turntable and extending upwardly therefrom, said spindle having an offset top portion with a shoulder at the bottom of said top portion for supporting the center of said records, with said records being positioned about said top portion, means on said top portion for aligning said records on said shoulder, the bottom of said aligning means being vertically spaced above said shoulder a distance substantially equal to the thickness of one of such records, a movable support for supporting the edge of said records having shelf portions of different lengths thereon, with movement of said edge support moving a shelf portion to a selected position so as to support the edge of a stack of records of a certain size, said shelf portions being vertically offset relative to each other and lying in horizontal planes parallel to the horizontal plane of said shoulder but out of said horizontal plane so that said records are supported at an angle inclined to the horizontal plane of said shoulder, the particular angle being dependent upon the selected position of said movable edge support, said angle serving to position the bottom one of said records on said shoulder free of said aligning means while retaining the remaining records in engagement with said aligning means, and means in said center support individually engaging the bottom one of said records in succession and moving the engaged record from said shoulder and said edge support so that it will drop into a playing position on said turntable.

4. In a sound reproducing unit, the combination with a rotary turntable for supporting a record in playing position, of means for supporting a stack of records above said turntable including a stationary spindle centered relative to said turntable and extending upwardly therefrom, said spindle having an offset top portion with a shoulder at the bottom of said top portion for supporting the center of said records, with said records being positioned about said top portion, means on said top portion for aligning said records on said shoulder, the bottom of said aligning means being vertically spaced above said shoulder a distance equal to the thickness of one of such records, a rotatable support for supporting the edge of said records having shelf portions of different lengths thereon, with rotation of said edge support to a selected position moving a shelf portion to support the edge of a stack of records of a certain size, said shelf portions being vertically offset relative to each other and lying in horizontal planes parallel to the horizontal plane of said shoulder but out of said horizontal

- plane, so that said records are supported at an angle inclined to the horizontal plane of said shoulder, the particular angle being dependent upon the selected position of said rotatable edge support, said angle serving to position the bottom one of said records on said shoulder free of said aligning means while retaining the remaining records in engagement with said aligning means, and means in said center support individually engaging the bottom one of said records in succession and moving the engaged record from said shoulder and said edge support so that it will drop into a playing position on said turntable.
5. In a phonograph record changing apparatus for changing various sized records each having a center opening with an enclosing edge, the means for supporting a stack of records above a playing position including a center support for successively supporting the records at the center opening edge of each, and a movable edge support, means spaced upwardly from said center support aligning a stack of records on said two supports, said aligning means being offset laterally relative to said center support, and having an annular edge at the bottom thereof, said edge support having a pair of shelf portions vertically spaced from each other and each being out of horizontal alignment with a horizontal line through said center support, one of said shelf portions being above said horizontal line and the other shelf portion being below said line, the center support and a corresponding shelf portion supporting a stack of records of one size so that said records are inclined in one direction relative to the horizontal at said center support, and alternatively a stack of records of another size are inclined in the opposite direction relative to a horizontal line at the center support, with a portion of the annular edge of the offset aligning means acting to engage the edge of the center opening of a second record in a stack, and means for ejecting the lowermost record of a stack from the center support while the second record is so engaged.
6. In phonograph record changing apparatus for changing various sized records each having a center opening with an enclosing edge, the combination including a vertical center spindle unit having a record support shelf and a record aligner having a bottom edge above said support shelf and with said aligner offset laterally relative to said shelf, record edge support means having a plurality of record support portions spaced apart in a vertical direction from one another and each support portion being out of alignment with a horizontal line through said support shelf and positioned relative to such a line that a stack of records of one size supported on said support shelf and a support portion is inclined in one direction relative to said line and alternatively a stack of another size supported on said support shelf and another support portion is inclined in another direction relative to said line, said record aligner bottom edge being spaced above said support shelf a distance such that it avoids the center opening edge of the lowermost record in an inclined stack but engages the center opening edge of a second record in such a stack and retains the same against lateral movement when the lowermost record is ejected, and means for ejecting the lowermost record in succession from said support shelf and a support portion.
